UNITED STATES PATENT OFFICE.

URIAH HOKE, OF CORNWALL, PENNSYLVANIA.

FILTER.

1,112,212.

Specification of Letters Patent. Patented Sept. 29, 1914.

Application filed May 20, 1913. Serial No. 768,740.

To all whom it may concern:

Be it known that I, URIAH HOKE, a citizen of the United States, and a resident of Cornwall, in the county of Lebanon and State of Pennsylvania, have invented a new and useful Improvement in Filters, of which the following is a specification.

My invention is an improvement in filters, and has for its object to provide a device of 10 the character specified, especially adapted to be attached to the discharge pipe from the collecting surface as for instance, a roof, and to be arranged between the said collecting surface and the cistern and having means 15 for thoroughly purifying and clarifying the water before admitting the same to the cistern, and also having means for deflecting the first water discharged from the collecting surface out of the filter and away from 20 the cistern.

In the drawings:—Figure 1 is a longitudinal section of the improved filter, Fig. 2 is a section on the line 2—2 of Fig. 1. Fig. 3, 4 and 5 are sectional views of modified 25 constructions, Figs. 3 and 4 showing the construction only partially, and Fig. 6 is a top plan view of Fig. 5 with a part of the cover broken away.

In the embodiment of the invention shown 30 in Figs. 1 and 2, a casing is provided, consisting of upper and lower sections 1 and 2 respectively, the said sections being of cylindrical form and the section 2 is provided with a supporting ornamental base 3. The 35 upper edge of the lower section 2 is annularly enlarged as indicated at 4, and the lower end of the upper section seats within the enlarged upper end of the lower section. The lower section is provided with a partition 40 or diaphragm 5, near its lower end, the said diaphragm being spaced above the base. A pipe 6 leads from above the diaphragm into the casing below the diaphragm, and thence through the side wall where it is provided with a valve casing or faucet 7. A frusto-conical auxiliary casing 8 is connected 45 with the upper face of the diaphragm 5, the said diaphragm closing the lower end of the auxiliary casing. The upper end of the auxiliary casing is closed as shown at 9, and a pipe 10 leads from the said upper end and thence extends laterally outside the lower section 2 of the casing just below the enlargement 4. The auxiliary casing is pro-

vided with two annular series 11 and 12 of 55 openings, the openings 12 being at the partition or diaphragm 5, and the openings 11 being spaced above the same. A pipe 13 extends through the diaphragm at the axis of the casing 1—2, the said pipe extending 60 through and beyond the base 3 of the casing and to a point near the top 9 of the auxiliary casing 8.

The section 1 of the main casing is provided near its lower end with a transverse 65 diaphragm 14 of perforate material, and the upper end of the said section is beaded as indicated at 15, and is engaged by a cover 16. A pipe 17 extends through the cover and a cup or receptacle 18 is arranged in the said section of the casing just below the pipe 17, the said pipe delivering to the cup. The cup 18 is provided with an outlet 19 in its bottom, and the said outlet delivers into the enlarged upper end 20 of a pipe 21. The pipe 75 21 is arranged adjacent to the side wall of the section of the casing, extending from the cup 18 to a point near the diaphragm 14, where the said pipe opens with a lateral elbow 22, through the side wall of the section 80 1 of the casing 1—2.

The section 1 of the casing is provided with a lateral opening 23, the edges of the opening being beaded as indicated at 24, to strengthen the same. The cup 18 is provided 85 on its outer face with oppositely arranged perforated lugs 25 and 26, and chains 27 and 28 respectively are connected with the said lugs. The chains extend through the opening 23, and the free end of the chain 27 is 90 provided with a ring 29 of larger diameter than the opening 23 to prevent the passage of the ring through the opening.

The cup is provided with a depending pin 30 at the center of its bottom, and the said pin extends into a bearing 31 formed in the periphery of the enlargement 20 of the pipe 21. The said pin supports the upper end of the pipe 21, holding it in a certain position with respect to the cup. The upper section 100 1 of the casing is partially filled with filtering material indicated by the reference numeral 32, the said material fitting around the pipe 21 and resting at its lower end on the diaphragm 14. The said material fills the 105 section of the casing to the enlargement 20 of the pipe 21. By means of the chains 27 and 28, the cup 18 may be rotated on the pin

30, to bring the outlet 19 thereof above the enlargement 20 of the pipe 21, or above the filtering material in the upper section of the casing.

5 It will be noted that the lower free edge of the outlet 19 of the cup is spaced above the upper free edge of the enlargement 20 to permit such rotation of the cup. When the outlet 19 is above the enlargement 20 of 10 the pipe, the water which enters the casing through the pipe 17 from the roof or other place of collection, passes through the pipe 20-21-22 to a suitable place of discharge without affecting or without interference 15 from the filter. When however, it is desired to filter the water and to pass it into the cistern, the cup 18 is oscillated, by means of the chains 27 and 28, to bring the outlet 19 thereof away from over the enlargement 20 of the pipe. The water now passes into the 20 upper section of the casing and down through the filtering material 32 into the lower section of the casing, passing through the perforated diaphragm as it leaves the 25 filtering material.

The pipe 13 communicates with the cistern, and whenever the water in the filter rises above the upper end of the pipe 13, it will flow into the cistern. A certain predetermined amount of water depending upon 30 the height of the upper end of the pipe 13, above the diaphragm 5 is always retained in the lower section of the casing and may be drawn off for use through the valve casing 35 or faucet 7. The water in the lower section of the casing enters the auxiliary casing 8 through the openings 11 and passes up in the said auxiliary casing until it reaches the top of the pipe 13 through which it flows 40 into the cistern.

In the construction shown in Fig. 3, the auxiliary casing 8 is replaced by a transverse partition or diaphragm 33, arranged in inclined position transversely of the lower 45 section 2 of the casing, and at its lowest point a discharge pipe 34 leads downwardly from the said partition to a point below the upper end of the discharge pipe 13. The escape pipe 35 for air leads from the partition 33 and opens through the side of the casing section in the same manner as the pipe 10. With this construction a certain amount of water will always be retained in the lower section 2 of the casing, since no 50 water can flow through the pipe 13 until the water reaches the upper end thereof. The trapped air below the partition 33 escapes through the pipe 35.

In the construction of Fig. 4, the discharge pipe 36 extends through the partition 5, and above the same, and the said pipe is provided with a gooseneck or return bent portion 37. The air discharge pipe 38 extends from the apex of the arched connection 60 between the body portion 36 of the said

pipe and the return bent portion 37. As the water passes through the perforate diaphragm 14, it must rise to the arched connection between the portions 36 and 37 of the said pipe before it can flow into the cistern. The trapped air escapes through the pipe 38.

The improved filter is arranged between the cistern and the place of collection, that is, between the roof and the cistern. The 70 discharge pipe from the roof connects with the pipe 17, while the pipe 13 delivers into the cistern. Thus the water will be thoroughly filtered and clarified before it reaches the cistern.

Any impurities in the way of sand and the like that may enter the lower section 2 of the casing will be deposited on the partition 5 and will not flow into the cistern. The upper portion 1 of the casing may be 85 easily removed for cleaning or for renewing the filtering material or any other purpose. The lower section is then accessible for cleaning or repairs.

As is known, the first water that runs 90 away from the roof is dirty, since it catches the impurities and dirt from the roof which has collected since the last rain. In use, the first discharge from the roof would be permitted to pass out through the pipe 20. As 95 soon as the water shows clear discharging from the said pipe, the cup 18 will be oscillated to deliver on to the filtering material.

It will be understood that the filter will be arranged as may be desired, between the 100 place of collection and the receptacle for the filtered water, and the arrangement will depend upon the relative position of the receiving and collecting elements. If for instance, the said receiving and collecting elements 105 are at the same level, the filter would occupy a position either horizontal or approximately so, and only such changes would be made as would be necessitated by the change in relative position. As for instance with the construction of Fig. 1, the discharge pipe 13 might be arranged as shown or the said pipe might extend laterally from the casing, and the trapping device would be changed to a horizontal position. A construction of this 110 character is shown in Figs. 5 and 6, wherein the casing 39 is provided at one end with a lateral extension 40, for receiving filtering material designated at 41, and a screen 42 is arranged between the casing 39 and the 115 extension. The casing is provided with a base 43, and with a diaphragm 44 just above the base. The casing is also provided with a lateral outlet 45, through the diaphragm, the outlet having a controlling mechanism 120 46 outside the casing. The discharge pipe 47 extends through the diaphragm and above the same, and the said discharge pipe may be straight, as shown, to deliver directly 125 below the casing or may be bent laterally as 130

indicated at 48 in dotted lines to discharge laterally with respect to the casing.

The casing and extensions are provided with a cover 49, and the inlet pipe 50 opens 5 through the cover at the end remote from the casing. The said inlet may be vertical as shown in full lines at 50 or may be lateral as shown in dotted lines at 51.

A cup 52 is arranged in the extension below the inlet pipe, the said cup having an outlet 53, delivering eccentrically to the cup, and a pin 54 depends from the center of the cup and engages a bearing 55 in the vertical portion of a partition 56 the said partition 15 comprising the vertical portion, as shown. The cup may be provided with chains 57, similar to the construction of Fig. 1, for rotating the cup to bring the outlet over the filtering material on one side of the 20 partition 56, or over the compartment separated from the body of the extension by the partition, the said compartment having a discharge outlet 57.

The filtering material is arranged between 25 the screen 42 and the partition 56. A frusto-conical shield or hood 58 incloses the upper end of the discharge pipe 47, the said hood being arranged with its small end upward, and the small end is provided with a trapped 30 air discharge pipe 59, the said pipe extending to near the cover 49 of the casing.

The shield or hood is provided with annular series of outlets 60, near and at its lower end for admitting the water within the hood, 35 the construction being practically the same as that shown in Fig. 1. The filtering material is arranged below a screen 61, and the operation is practically the same as the construction of Fig. 1.

40 The first flow from the place of collection is discharged through the discharge outlet 57, and as soon as the water from the said outlet shows clean, the cup 52 is rotated to bring the outlet 53 above the filtering material. The water flows down through the filtering material and through the screen 42

into the casing proper. Here it passes through the opening 60 and when it rises above the upper end of the discharge pipe, the water may flow into the place of storage. When 50 the cover 49 is removed, access is permitted to the interior of the casing, for cleaning the same or for removing the filtering material and replacing it with fresh material.

The portion 40 of the casing is described 55 as an extension for convenience. The casing however, comprises both the vertical portion 39 and the horizontal portion 40. The construction shown in Figs. 5 and 6 may be arranged between the place of collection and 60 the place of storage for the water when the relative height of the said place of connection and place of storage is not so pronounced. When the place of connection is at considerable height above the place of 65 storage, the form shown in Figs. 1 to 4 are preferable.

I claim:—

A filter comprising upper and lower sections detachably connected together, the 70 lower section having a base and a bottom above the base and provided with a delivery pipe extending through the bottom, the upper section having a transverse perforated partition near its lower end for supporting 75 filtering medium, a waste pipe held in the upper section at one side thereof and delivering laterally from the section near the partition, a removable top for the upper section having an inlet pipe extending through 80 the same, means between the said inlet pipe and the waste pipe for receiving the water from the inlet pipe and delivering it to the waste pipe or to the interior of the filter, and means in the lower section in connection 85 with the delivery pipe for preventing the direct flow of the water from the filter through the delivery pipe.

URIAH HOKE.
